UNITED STATES PATENT OFFICE

RALPH H. MCKEE, OF LEONIA, NEW JERSEY

DENATURED SPIRITS AND METHOD OF MAKING THE SAME

No Drawing.

Application filed May 9, 1925. Serial No. 29,219.

This invention relates to denatured spirits and methods of making the same. By spirits, I refer to either ethyl alcohol or methyl alcohol either in the anhydrous form or mixed with small amounts of water, e. g., 95 per cent. ethyl alcohol, or 95 per cent. methyl alcohol.

An object of the invention is to provide a denaturant for use in the preparation of spirits for scientific and industrial purposes which is more readily soluble in spirits than similar materials now employed, whereby removal of the denaturant for the purpose of unlawfully using the alcohol in the manufacture of beverages or for other purposes, is rendered more difficult.

A further object of the invention is to provide a denaturant having a stronger and more unpleasant taste than materials now employed.

In carrying the invention into effect, I employ shale oil from which the saturated hydrocarbons have been removed by treatment with liquid sulfur dioxide, a process similar to the Edeleanu process of refining ordinary well petroleum. By this means, I obtain unsaturated hydrocarbons of the olefinic series having but a small percentage of unsaturated hydrocarbons present, such as heptane, octane, nonane, decane, and traces of similar hydrocarbons of the series C_nH_{2n+2} . I prefer as a denaturant that portion distilling in the gasoline boiling range.

These olefinic hydrocarbons are employed as a denaturant for spirits in substantially the same manner that ordinary hydrocarbons of the gasoline boiling range are now employed for the treatment of spirits for scientific and industrial purposes and to thereby render the alcohol unfit for beverage purposes. The new denaturant may be mixed with 95 per cent. ethyl alcohol in substantially any desired ratio, e. g., equal parts even at freezing temperature, whereas ordinary hydrocarbons of the gasoline boiling range can be added only in very small amounts, particularly at winter temperatures. The increased solubility of the olefinic hydrocarbons in thus a material advantage in denaturing alcohol. My pre-

ferred procedure is to add to 100 volumes of the spirit 5 to 10 volumes of the lower boiling olefinic hydrocarbons and stir.

A further advantage incident to the use of the olefinic hydrocarbon is that it is not necessary to use benzene or toluene as a third or blending component to bring about the mixing of the spirit and the hydrocarbon.

As stated, the mixing of the denaturant and the spirits may be done in any suitable way and the denaturant may be employed in substantially the same proportion as ordinary hydrocarbons of the gasoline boiling range are now employed or in greater proportion if desired.

If desired, the pyridine and alkylated pyridine from the shale oil may be used with the olefinic hydrocarbons employed as a denaturant, which will give the denatured spirits an odor of pyridine as well as an odor of the olefinic hydrocarbons, and also increase the difficulty of any attempt to remove the denaturant. The term "pyridine" as employed in certain of the claims contemplates within its scope not only ordinary pyridine but any of the pyridines present in or derived from shale oil.

It is well known in the art that the amounts of nitrogen compounds of the pyridine type present in shale oil are quite minor. In general, the proportion is of the order of one to three per cent., although in some cases it may run slightly higher or lower, and in one exceptional case has been known to amount to ten per cent. The same percentages of pyridine hold true in the case of that portion of the shale oil which distills in the gasoline range, as holds true for the shale oil as a whole.

A mixture of these olefinic hydrocarbons and spirits manufactured for industrial purposes is far more difficult to separate into the alcohol and the denaturant for the purpose of obtaining alcohol that can be used in the manufacture of beverages than is alcohol denatured with ordinary hydrocarbons of the gasoline boiling range or other denaturants now employed.

The term "unsaturated hydrocarbons of

shale oil" as employed in certain of the claims contemplates within its scope olefinic hydrocarbons obtained from shale oil and containing small amounts of incidental impurities, such as, for example, approximately 10 per cent. of saturated hydrocarbons and unsaturated hydrocarbons of other than the olefinic series. Substantially all of this material distils in the gasoline boiling

range.

10 While I have described in detail the preferred practice of my process, it is to be understood that the details of procedure may be widely varied without departing

15 from the spirit of the invention or the scope of the subjoined claims.

I claim:

1. The process of denaturing an alcohol which comprises adding thereto a liquid 20 fraction of shale oil freely soluble therein and having an exceedingly unpleasant taste, said fraction comprising unsaturated olefinic hydrocarbons distilling in the gasoline boiling range.

2. The process of denaturing an alcohol which comprises adding thereto a liquid fraction of shale oil freely soluble therein and having an exceedingly unpleasant taste, said fraction comprising pyridines and unsaturated olefinic hydrocarbons distilling in 30 the gasoline boiling range.

In testimony whereof, I affix my signature.

RALPH H. MCKEE.
